UNITED STATES PATENT OFFICE.

JOSEPH R. MARTINEAU, OF PHILADELPHIA, PENNSYLVANIA.

DESIGN FOR A FABRIC FOR CHILDREN'S CARRIAGES.

SPECIFICATION forming part of Design No. 19,566, dated January 7, 1890.

Application filed December 3, 1889. Serial No. 332,467. Term of patent 14 years.

To all whom it may concern:

Be it known that I, JOSEPH R. MARTINEAU, a citizen of the United States, residing at Philadelphia, in Philadelphia county, State of Pennsylvania, have invented and produced a new and original Design for a Fabric for Use in Children's Carriages and other Structures, of which the following is a specification, reference being had to the accompanying drawing, forming part thereof, which represents a plan of the design.

This design consists of a fabric having certain approximately-oval figures arranged therein in lateral series, as indicated at 1 1 1, and in endwise series, as indicated at 1 2 2. These ovals are joined laterally at their sides, the parts 3 and 4 of the willow, rattan, or other material which composes them being placed with reference to each other in a form, broadly considered, resembling or suggestive of the figure 8. Of the two parts or members constituting the side of a so-called oval one is turned at the end of the oval to the left—as 3, for example—and passes around a

corresponding part of another oval situated 25 end to end with the first named, while the other member—as 4, for example—similarly embraces its counterpart at the right.

Though parts of the herein-described design have some resemblance to an oval slightly 30 compressed at its sides, and also to the figure 8, it is only in a broad sense that they can be thus described, and their particular form as well as their general effect when combined, as set forth, will be best understood by reading the above description in connection with the drawing herewith.

Having thus described the novel design, I claim and desire to secure by Letters Patent—

The design for a fabric, as described and 40 shown.

In testimony whereof I affix my signature in presence of two witnesses.

JOSEPH R. MARTINEAU.
